FUSE

Cecil C. Fawcett, Philadelphia, and John J. Hart,
Bryn Mawr, Pa., assignors to the United States
of America as represented by the Secretary of
War

Application December 15, 1939, Serial No. 309,417

2 Claims. (Cl. 102—82)

(Granted under the act of March 3, 1883, as
amended April 30, 1928; 370 O. G. 757)

1

The invention described herein may be manufactured and used by or for the Government for governmental purposes without the payment to us of any royalty thereon.

This invention relates to a fuse.

The purpose of the invention is to provide a structure in which a base plug for a mechanical time fuse may conveniently carry a compressed pellet of black powder or other relay charge in its front face and in which flame communication to a central flash passage is provided by means of a disk interposed between the base plug and the fuse body.

The specific nature of the invention as well as other objects and advantages thereof will clearly appear from a description of a preferred embodiment as shown in the accompanying drawings in which:

Fig. 1 is a longitudinal sectional view through a portion of a fuse;

Fig. 2 is a sectional view on the line 2—2 of Fig. 1.

Referring to the drawings by characters of reference there is shown a portion of a mechanical time fuse comprising a body 5 carrying a clock-work mechanism indicated generally by its frame 6 and including a firing pin 7 and a primer 8. A flash passage 9 leads from the primer to a cavity 10 in the rear end of the body.

A base plug 11 fitting in the cavity 10 and secured to the body by the threaded engagement 12 is formed with an annular groove 13 in the marginal portion of its front face. Black powder compressed in the groove forms a ring pellet 14 which is radially spaced from the axis of the fuse by the same amount as the primer 8 and flash passage 9.

A shallow recess 15 formed centrally in the front face of the base plug and spaced from the groove 13 is in communication with a reduced passage 16 and includes an annular shoulder 17.

The passage 16 is preferably tapered and may be closed at the rear face of the base plug by a thin disc 18 which is readily perforated by the flame from the pellet 14. In the fuse for which the present improvement is made the passage 16 has an extremely wide mouth to extend beyond the flash passage 9 and it receives a bag of loose powder.

A spacing disk 19 fitting in the recess 15 and seated on the shoulder 17 has a thickness in excess of the depth of the recess 15 so that upon assembly the marginal front face of the plug will be spaced from the opposite face 20 of the body. The disk is provided with a plurality of openings

2

21 conveniently formed by marginal indentations which are of sufficient radial dimension to extend inwardly from the inner edge of the shoulder 17.

In operation the flame from the primer 8 ignites the black powder pellet 14 and the flame from the pellet is free to pass to the openings 21 by virtue of the spacing between the marginal front face of the plug and the face 20 of the fuse body. The flame after passing through the openings 21 is directed through the passage 16 to a booster charge not shown.

We claim:

1. In a fuse, a body having a cavity, a base plug in the cavity of the body, said plug having a recess in its front face and a communicating flash passage reduced to provide a shoulder, a disk fitting in the recess and seated on the shoulder of the plug, said disk having a thickness in excess of the depth of the recess to space the marginal face of the plug from the fuse body, said disk formed with marginal openings establishing communication between the recess and passage in the plug, and an annular powder pellet carried in the marginal face of the plug.
2. In a fuse, a body having a cavity, a base plug in the cavity of the body and having a central passage, an annular powder pellet carried in the marginal face of the plug and radially spaced from the central passage, a disk interposed between the plug and body above the central passage of the plug and spacing the marginal face of the plug from the body, and openings in the disk establishing flame communication between the central passage and the powder pellet in the marginal face of the plug.
